GRENADE

John D. Steel, Fort Worth, Tex.

Application March 17, 1941, Serial No. 383,800

2 Claims.

(Cl. 102—2)

This invention relates to explosive bombs or grenades of the type which may be employed with fire arm projectors, released from airplanes or manually projected, and it has particular reference to a device embodying a compact assembly adapted to afford a weapon capable of numerous adaptations, and its principal object resides in the provision of a grenade of maximum efficiency yet having dependable safety features calculated to prevent premature explosion.

A further object of the invention resides in the provision of a firing arrangement comprising a firing pin and percussion cap adapted to be assembled in one end of the casing capable of being locked in firing position to be released on contact with some object, such as the ground, and a locking device designed to retain the firing assembly in firing position until released by the air current acting upon a propeller connected with the locking mechanism.

Yet another object of the invention resides in the provision of a visible indicator or signal adapted to indicate the position of the firing pin from the exterior of the casing providing a means whereby the internal condition of the grenade can be determined at all times from the exterior of the assembly.

While the foregoing objects are paramount, other and lesser objects will become manifest as the description proceeds taken in connection with the appended drawing wherein:

Figure 1 illustrates the invention, partially in cross section, showing one half of the casing removed and depicting the firing pin assembly in firing position.

Figure 2 is a fragmentary cross sectional illustration of the visible indicator assembly by which the position of the firing pin assembly is determined exteriorly of the casing.

Figure 3 is a perspective illustration of one half of the casing.

Figure 4 is a vertical cross sectional view of the firing pin and percussion cap arrangement, taken on lines 4—4 of Figure 5, and showing the firing pin in firing position.

Figure 5 depicts in plan the firing pin assembly inserted from the bottom of the casing, taken on lines 5—5 of Figure 1.

Figure 6 is a lateral cross sectional view taken on lines 6—6 of Figure 1 illustrating the manner in which the two halves of a casing are secured.

Figure 7 is a plan view of the invention showing the scored outer walls of the casing and illustrating the propeller which functions to release the locking device for the firing pin assembly and

depicts the locking device for the propeller providing a safety arrangement and capable of operation through the medium of a cord shown in Figure 1.

Accordingly, therefore, the invention comprises an assembly which is encased within a housing 1, illustrated particularly in Figure 1, preferably formed in two parts 2 and 3, the latter being shown in perspective in Figure 3. The primary portion 2 of the housing 1 is formed with a conical integral member 4 at one end having a bore 5 therethrough, the purpose of which will be hereinafter shown.

Since the device may be adapted to distribution from the air it is desirable, although not necessary, that the housing 1 be streamlined and provided at its smallest end with fins 6, as illustrated in Figure 1. Around the upper ends of the fins 6 there is arranged a band 7 designed to protect the mechanism arranged therewithin and which will be presently described. The opposite half of the casing 3, shown in Figure 3, is formed to be adjusted to the member 2 so that the projecting flanges 8 may be received by bosses forming recesses 9 in the member 3 and in order that the resulting contact between the two members may be properly sealed. The upper end of the member 3 is recessed at a to receive the depending semi-circular shoulder b integral with the member 4 heretofore described.

The bottom of the housing 1 is formed by a circular member 10 having an annular indentation 11 therearound, as shown in Figures 1 and 5, adapted to be received by the lowermost rim of the two members 2 and 3 of the housing 1.

The circular member 10 is provided with a central integral tubular member 12 adapted to extend upwardly into the housing 1, in the manner illustrated in Figure 1, and having its upper end threaded at c by which it is secured within the member 4. The firing pin assembly, illustrated in detail in Figure 4, is secured to the member 10 and extends horizontally thereon adjacent to the tubular member 12, as illustrated in Figure 5. This assembly consists of a tubular housing 13 having a thickened portion 14 on one end adapted to receive a percussion cap 15 positioned to be engaged by a firing pin 16 arranged in the opposite end of the casing 13. The firing pin is provided with a head 17 by which the pin 16 is retained in firing position, as shown in Figure 4, through the medium of a lock 18 against tension of a spring 19. Obviously, when the lock 18 is withdrawn from behind the head 17 the pin 16 will be actuated by the spring 19 against the per-

cussion cap 15 to explode the charge within the casing 1. The operation of the assembly, however, will be described in greater detail presently.

The lock 18 is rigidly secured through an arm 20 to the upper end of a plunger 21 having a contact button 22 rigidly connected to its lowermost end, as illustrated in Figure 1. The plunger 21 is operatively arranged within a bore 23 forming a continuation of the tubular member 12 through the member 10 which forms the bottom closure of the housing 1. The lock 18, therefore, is released from the firing pin 16 when the button 22 comes in contact with some object with sufficient force to urge the plunger 21 upwardly.

As a precaution against the premature releasing of the firing pin, a locking assembly is provided which operates within the tubular element 12, previously described, and comprises a tubular shaft 24 rotatably disposed within the member 12 and having a propeller 25 attached to its uppermost end. The propeller is retained against rotation by a pin 26 detachably secured through a bracket assembly 27 rigidly fixed to the conical end of the housing 1, as shown in Figure 1, or at the upper end of the integral member 4. The bracket assembly 27 is partially supported by the fins 6 and provides a rigid anchorage for the pin 26 to which is connected a cord 28, of silk or the like, the opposite end of which may be coiled and anchored so that when the grenade is dropped the pin 26 is withdrawn from the bracket assembly 27 permitting the propeller 25 to rotate.

The hollow shaft 24 is secured within the tubular element 12 against longitudinal movement by a bearing 29 arranged around its lowermost end, as shown in Figure 1. Another bearing 30 is provided at the upper end of the member 12 insuring smooth operation of the tubular shaft 24.

A stationary rod 31 is arranged through the tubular shaft 24, as illustrated in Figure 2, having its lowermost end threaded at d to correspond with the interiorly threaded lower end of the shaft 24 so that as the latter is rotated the rod 31 is moved longitudinally within the shaft 24, retained against rotation by a fluted member 32 engaged by small grooves 33 within the lowermost end of the tubular member 12.

The member 32 is urged downwardly against the upper end of the plunger 21, as illustrated in Figure 1, to retain the lock 18 in position against the firing pin head 17 and prevent the operation of the firing pin assembly until the member 32 is disengaged therefrom by the rotation of the tubular shaft 24 by the propeller 25 when acted upon by air currents.

The invention is assembled by inserting the threaded upper end c of the tubular member 12 into the integral portion 4 of the housing 1 and threading the same therewith until the closure member 10 at the bottom of the housing 1 is in position, as illustrated in Figure 1. The charge is placed within the member 2 of the housing 1 and the lock 18 is inserted behind the head 17 of the firing pin 16, in the manner illustrated, and the rod 31 is threaded downwardly by the propeller 25 until the member 32 engages the upper end of the plunger 21 forming an integral part of the button 22.

After the charge is inserted and the firing pin assembly placed in firing position, in the manner just described, the opposite section 3 of the housing 1 is placed in position and secured to the member 2 by screws 34, or the like, inserted through bosses 35 in the member 3 and threaded

into corresponding bosses 36 in the member 2, in the manner illustrated in Figure 6. Unless the firing pin assembly is placed in firing position prior to closing the housing 1 the upper end of the rod 31 would project above the upper end of the tubular shaft 24, indicating that the firing assembly is not in proper position. Thus a visible signal is provided at all times whereby it may be readily determined whether or not the invention is in proper working condition.

The propeller 25 and the safety pin assembly 26 are protected by the band or guard 7 previously referred to and illustrated in Figure 1, thus preventing any injury to any part of this arrangement while the invention is being transported or handled. The release of the lock 18 of the firing pin assembly is entirely dependent upon the rotation of the propeller 25 which rotates the shaft 24, in the manner previously described, causing the rod 31 to move longitudinally within the said shaft toward and away from the upper end of the plunger 21 permitting the same to move upwardly and release the lock 18 from the firing pin 17 when the button 22 comes in contact with some object, only the slightest force being necessary to release the firing pin assembly.

Obviously, the invention is perfectly safe for handling, shipping and even assembling, when the firing pin assembly is in the position illustrated in Figure 1 and locked by depressing the member 32 against the upper end of the plunger 21, in the manner just described. As long as the propeller 25 is retained by the pin 26 against rotation the rod 31 cannot be moved longitudinally within the tubular shaft 24. When the rod 31 is urged upwardly within the shaft 24, however, the upper end of the said rod will appear above the propeller assembly and indicate that the firing pin assembly is not in the proper position so that the invention may be opened and the firing pin locked in firing position by the lock 18, in the manner previously described.

Manifestly, the structure herein shown and described is capable of considerable changes and modifications from time to time by those skilled in the art and such changes and modifications as may be resorted to which may be considered as coming within the spirit and intent of the invention may also be considered as coming within the scope of the appended claims.

What is claimed is:

1. A grenade of the type adapted to explode upon impact, including end members, a tubular member connecting the same, a firing pin mounted on and movable transversely of one end member, a percussion cap in the path of the firing pin, a pin-actuating spring, a plunger mounted to slide in said end member and projecting therebeyond, a lock connected to the plunger and normally engaging and restraining the firing pin, a non-rotatable screw-threaded element mounted to slide within the tubular member and normally positioned to hold the plunger and lock against sliding movement, a hollow shaft journalled in the other end member and rotatably mounted in the tubular member, said hollow shaft being held against longitudinal movement and being in engagement with the threaded element, a propeller wheel secured to the tubular shaft, opposed casting members for holding an explosive and proportioned to embrace the end members and bridge the space therebetween, and means for clamping the casing members together and upon the end members to hold all of said members assembled.
2. A grenade of the type adapted to explode

upon impact, including end members, a tubular member connecting the same, a firing pin mounted on and movable transversely of one end member, a percussion cap in the path thereof, a pin-actuating spring, a plunger mounted to slide in said end member and projecting therebeyond for impact against an objective, a lock connected to and movable with the plunger and normally engaging and restraining the firing pin, a non-rotatable rod mounted to slide within the tubular member and normally holding the plunger against sliding movement in one direction, said rod having a screw-threaded portion, a hollow

5 shaft journalled in the other end member and rotatably mounted in the tubular member, said hollow shaft normally housing the rod and engaging the threaded portion thereof, a propeller wheel secured to the tubular shaft and constituting means, when rotated, for rotating the hollow shaft and feeding the rod longitudinally, said rod being proportioned to project outwardly from the hollow shaft when moved from normal position, and an explosive-containing casing connecting the end members and surrounding the space therebetween.

JOHN D. STEEL.
